UNITED STATES PATENT OFFICE

2,050,439

UTILITY CUTTER TOOL

Curt Marx, New York, N. Y.

Application September 21, 1934, Serial No. 744,921

1 Claim. (Cl. 30—9)

The main object of this invention is to provide a cutting implement for textiles or similar other material which device is simple in cost and construction and easy to assemble.

Another object of the invention is to provide a cutting tool for textiles and the like which is so constructed as to have its knife edge ordinarily a razor blade mounted within a guard which adjusts the depth of the cut by said implement.

The above and other objects will become apparent in the description below in which characters of reference refer to like-named parts in the drawing.

Referring briefly to the drawing, Figure 1 is a perspective view of the preferred type of cutting implement showing the same completely assembled.

Figure 2 is a longitudinal, sectional, elevational view thru the case handle of the implement showing the mounted plates within said casing.

Figure 3 is a longitudinal, sectional side elevational view thru the casing showing the cutter holding plates therein.

Figure 4 is a perspective view of one of the cutter holding blades.

Figure 5 is a side elevational view of the modified type of implement showing a guard secured to one end of the implement.

Referring in detail to the drawing the numerals 10 and 11, indicate the cutting blade holding plates used with the device. These plates represent elongated members which lie one upon the other and at one end have a razor blade 12, inserted between them. The plate 11, is provided with a pair of circular bosses 13, which register in similarly positioned openings 14, formed in the plate member 10. The upper edge of one end of the plates 10 and 11, is recessed marginally as indicated by the numeral 15, and the opposing edge 16, of these plates are cut away angularly as indicated by a numeral 17, expose a greater portion of the razor blade holding plates 10 and 11, are provided with grooves 18, which are curved longitudinally and serve as finger inserts when it is desired to separate the plates after removing the same from an irregularly formed rectangular casing in which the plates are normally based. This casing has end walls 19 and 20, and side walls 21, and 22, and at one end has its side walls formed into tapering tongues 23, as indicated in Figure 1. The rear ends of the plates 10 and 11, are ser-

rated transversely as indicated by the numeral 24. The modified form of device is identical to the preferred form but in addition is connected with a guard which has a recessed rim 25. The latter resting upon the edge 26, of the tapered portion 5 of the casing and is so constructed as to have an angular portion 27, thereon thru which a corner of the razor blade 12, may be adjustably exposed.

In use the device is adapted to cut such articles 10 as awning material, plush and similar other textile material. A large depth of blade may be used when exposing the blade 12, beneath the angular cut out portion beneath the plates 10 and 11, and a narrow depth may be used when exposing the razor blade thru the recess of the plates. The plates 10 and 11, are slidably mounted within the casing and holder of the implement which may be slit out thru one or the other end of the same. In the modified type of implement shown 20 in Figure 5, a guard is mounted upon the tapered end of the casing of the angular corner 27, and this guard serves as a means of controlling the depth of cut of the razor blade when the plates 10 and 11, are adjusted and shifted, a predetermined distance within the casing.

It is to be noted that certain changes in form and construction may be made without departing from the spirit and scope of the invention.

I claim:

In a device of the class described a hollow casing having a tapered end, the extremity of said end being rounded, a pair of plates slidably mounted therein and being exposed partly beyond the tapered end of the casing, one edge of said 35 plates being marginally recessed, said plates being adapted to receive a razor blade between them, bosses on one of said plates, the opposing plate having openings therein in which said bosses are adapted to register, and said bosses being adapted 40 to receive a razor blade thereon and a guard adapted to be slipped over the tapered end of said casing, one of said corners of said guard being angularly cut away, said plates when shifted being adapted to expose more or less of said razor 45 blade thru said cut away portion and said guard to control the depth of cutting of said blade, said guard being so formed as to frictionally cling to said casing on the tapering and rounded end thereof.

CURT MARX. 50
